CLAIM

The ornamental design for a combined bottle and applicator for suntan lotion, as shown and described.

DESCRIPTION

FIG. 1 is an exploded perspective view of a combined bottle and applicator for suntan lotion showing my new design;

FIG. 2 is a front elevational view thereof, the side opposite being identical to the side shown;

FIG. 3 is a side elevational view thereof the side opposite being identical to the side shown;

FIG. 4 is a top plan view thereof;

FIG. 5 is a bottom view thereof; and,

FIG. 6 is a fragmentary front elevational view shown without the cap for clarity of illustration.

FIG. 1

FIG. 2

FIG. 3

FIG. 4

FIG. 5

FIG. 6
